TWIN ENGINE-OVER-WING AIRPLANE

David G. Blattner, Mercer Island, and Robert H. Drinnon, Kent, Wash., and Stefano P. Ruocco, Chiavari, Italy, assignors to The Boeing Company, Seattle, Wash.

Filed Jan. 22, 1973, Ser. No. 325,286

Term of patent 14 years

Int. Cl. D12—07

U.S. Cl. D12—80

FIG. 4

FIG. 1 is a top plan view of a twin engine-over-wing airplane of our new design;

FIG. 2 is a front elevational view;

FIG. 3 is a side elevational view; and

FIG. 4 is a side elevational view thereof.

The broken line disclosure of landing gear is for illustrative purposes only.

We claim:

The ornamental design for a twin engine-over-wing airplane, as shown and described.
